J. J. HINES AND H. R. WAY,
AUTOMATICALLY OPERATING WEATHER STOP,
APPLICATION FILED FEB. 19, 1921.

1,426,737.

Patented Aug. 22, 1922.

J. J. Hines and
H. R. Way.

By James J. Sheehy, *Attorneys*

UNITED STATES PATENT OFFICE.

JOHN JAMES HINES AND HENRY ROBERT WAY, OF HALIFAX, NOVA SCOTIA, CANADA.

AUTOMATICALLY-OPERATING WEATHER STOP.

1,426,737.

Specification of Letters Patent. Patented Aug. 22, 1922.

Application filed February 19, 1921. Serial No. 446,352.

To all whom it may concern:

Be it known that we, JOHN JAMES HINES and HENRY ROBERT WAY, citizens of Great Britain, residing at Halifax, in the Province 5 of Nova Scotia and Dominion of Canada, have invented new and useful Improvements in Automatically-Operating Weather Stops, of which the following is a specification.

Our present invention pertains to automatically operating weather strips for doors, windows, and the like and it contemplates the provision of a device whereby when the window or door to which it is applied is closed, the weather strip will be automatically operated to prevent wind, draught, 15 rain or snow from gaining access to the building or apartment equipped with our device.

The invention also contemplates means whereby the device may be made inoperative, such as for instance in mild or favorable 20 weather.

The invention further contemplates the provision of a device that is readily applied, 25 and easily removed from a door or window, and one that will lend quite a finished appearance and harmonize with other hardware at present used by builders in producing finished and up-to-date apartments and 30 buildings.

The invention in all of its details will be fully understood when read in connection with the drawings accompanying and forming part of this specification, in which:

35 Figure 1 is a perspective view illustrating our novel device as applied to a door.

Figure 2 is a longitudinal sectional view of the weather strip casing and illustrating the operating mechanism of the device.

40 Figure 3 is a sectional view taken in the plane indicated by the line 3—3 of Figure 2 looking in direction of arrows.

Figure 4 is a view similar to Figure 3 but taken in the plane indicated by line 4—4 of 45 Figure 2.

Figure 5 is an end elevation of the door showing in dotted lines portion of member 3. The view for purposes of illustration eliminates the casing 2 but discloses the trip 50 18 as confined between the member 3 and door 1 when the door is closed.

Similar numerals of reference designate corresponding parts in all the views of the drawings.

55 The door 1 and casing 2 are of the ordi-

nary well known construction and secured in the door casing 2 is a trip 3.

Properly secured to the lower end of the door is the outer casing 5, having the upper flat portion in which are provided apertures 60 for the reception of screws 4 or other fastening means for the connection of said casing to the door. This casing 5 is merely a covering for the working elements of our invention, and may be provided with the 65 lower rolled portion 6. This casing naturally is stationary.

A stationary plate 5' is also secured to the door through the medium of the fastening members or screws 4 and rests between 70 the casing 5 and the door 1, and said fastening screws pass first through the casing 5 and then through the stationary or back plate 5' and finally are secured in the lower end of the door 1. Secured to the back or 75 stationary plate 5' either by rivets or in any approved manner are ribs 10 that by preference are arranged in pairs equi-distantly throughout the length of the plate 5', and pivotally secured in the lower end of the 80 ribs is a rod 9 that supports the inner or movable casing 7 of my novel device.

Arranged between the series of ribs 10 are members 7' that are secured to and are movable with the rod 9 and the said members 7' 85 form an integral part of the movable casing 7. These members 7' are cut away near the upper end as illustrated in Figure 3 and pivotally secured in the upper end of the ribs 10 are aligned rods 13 and 131 on each 90 of which is provided a member of the clutch 19. The rod 13 is surrounded by a spring 14 which in turn is secured at one end to the casing 7 and at its opposite end the said spring 14 is secured to a collar 16 fast on the 95 rod 13. The rod 131 is provided with a spring 15 and on the extreme outer end of rod 131 we produce the trip 18.

The rods 131 and 13 may be operated as a unit by turning the trip 18 to the position 100 shown in Figure 2 when the clutch will assume the position shown in said figure.

Our device is simple in construction and operation and may be quickly applied and when a building or other structure is 105 equipped with the device, draughts are precluded entering said building or buildings and hence the danger of colds and diseases to the tenants of the same is materially decreased.

The invention is particularly adapted for use in large office and school buildings and in company with the advantages set forth, it also tends to reduce the amount of fuel used in heating such buildings. Moreover, dust and dirt gaining access to the building is prevented by our device which feature reduces the expensive outlay for labor now employed for cleaning a large building as well as wear on the furniture and contents of said building.

The pulling of the rod 131 outwardly and turning of the trip 18 upwardly will prevent said trip from being operatively engaged by member 3 when the door is closed.

The rods 13 and 131 carry eccentrics 17 that rest between the sets of ribs 10 and these eccentrics 17 are adapted to engage the cut away end of the portions 7'. As the portions 7' are movable with the casing 7 and because of the contact of these eccentrics 17 with the upper end of the portions 7', clockwise movement or the revolving of the rod 13 with respect to the lugs 10 will naturally impart rotary motion to the eccentrics and in turn operate the casing 7. The casing 7 is provided, when deemed necessary with the lower channel to receive a strip 8 of rubber or other weather stripping material.

In the practical use of the invention, when it is desired in cold weather to employ our invention, it is simply necessary to push the rod 131, inwardly to lock the clutch 19. The door is then closed and contact of the trip 3 with the trip 18 will cause the cam 18 to assume the position shown in Figure 5. This movement of trip 18 will cause the rods 13 and 131 to rotate and the eccentrics 17 engaging the upper ends of the portions 7' will manifestly tend to rotate the casing 7 on its axis (the rod 9) and hence the casing will be forced downwardly toward the sill or flooring and the strip of rubber or other material will snugly and firmly grip said sill or floor. Upon release of the trip 18 from its complementary trip 3, by opening of the door 1, the casing 7 will be returned to its inoperative position due to the action of the springs 14 and 15 on rods 13 and 131 which were under tension when the door was closed.

It will be manifest that the device is automatic in operation, and may either be set for use or the clutch 19 released to prevent operation of the device in mild weather. It will also be seen that because of its automatic arrangement, marring of a floor or

the difficult opening of the door is eliminated and this without the necessity of manually releasing the casing from its operative position. Moreover, this arrangement relieves the necessity of removing the device in warm weather and the annoying replacing of the entire device in cold weather.

We would distinctly have it understood our device is so constructed that the trip 18 by simply throwing the same so that it assumes a position opposite that shown in Figure 5 may be prevented from operating when desired.

Having described our invention, what we claim and desire to secure by Letters-Patent is:—

1. In an automatically operated weather stop, the combination of a back plate, an outer stationary casing secured to the upper end of the back plate, a series of ribs formed on the back plate, rods arranged in alignment with each other in and rotatable with respect to the ribs, a clutch adapted to couple and rotate said rods as a unit, cams of eccentric form arranged on the rods, members movably arranged on the lower end of the back plate and having surfaces actuatable by the cams and a movable casing formed integral with the members; one of said rods being provided with a trip adapted to rotate the rods when the clutch is thrown into operative position.

2. In a device for the purpose set forth, the combination of a plate, a stationary casing secured thereto, ribs arranged on the plate, rotatable rods secured in alignment in the ribs, eccentrics mounted on the rods, a clutch member arranged on each of the rods, said members adapted to connect said rods to move as a unit, a trip lever mounted on the end of one rod, a movable casing, members formed integral with the casing and pivotally mounted on the lower ends of said ribs, and portions formed in the members and adapted to engage the eccentrics of the rotatable rods, and a spring on one of said rods adapted to raise the movable casing, and weather stripping secured in the lower end of the movable casing.

In testimony whereof we have hereunto set our hands in presence of two subscribing witnesses.

JOHN JAMES HINES.
HENRY ROBERT WAY.
